REINFORCED METAL RAILROAD TIE

REINFORCED METAL RAILROAD TIE. This invention relates to new and useful improvements in railroad ties of the metallic type. The main object of the present invention consists in providing a railroad tie assembly, consisting of two channel sections held back to back, with a depression of appropriate width for each rail and lugs projecting over the rail base in such a manner that after assembly of the channelled sections and rails, the latter, when filling the depression and held by means of the lugs in said depressions, will lock the tie assembly against any longitudinal displacement of the channelled sections relative to each other.

Other objects and advantages of the invention will become apparent to the reader of the following specification.

In the drawings:

Figure 1 represents a fragmentary top plan view showing one of the ties for two rails.

Figure 2 is a fragmentary sectional view taken substantially on the line 2—2 of Figure 1.

Figure 3 is a perspective view of one section of the tie.

Figure 4 is a perspective view of the section of the tie.

Figure 5 is a perspective view showing both sections of the tie in assembled relation.

Figure 6 is a fragmentary side elevational view showing one end of the tie section shown in Figure 3.

Figure 7 is a fragmentary sectional view taken substantially on the line 7—7 of Figure 2.

Figure 8 is a fragmentary plan view of a modified form.

Referring to the drawings wherein like numerals designate like parts, it can be seen in Figures 3, 4 and 5 that the tie 5 is made of a pair of channelled sections denoted by reference characters A and B. Each of these sections has its flange portions disposed horizontally, the central webs or walls of the channelled sections A and B being bolted together as disclosed in Figure 7. One of the sections, such as the section B, has its ends notched as at 6, while the corresponding ends of the other section A are provided with lugs 7 bent out at right angles from its web. The lugs 7 when the tie is assembled are disposed through the notches 6 of the section B, thus locking both sections firmly together.

Each of the channel sections A, B in its uppermost horizontal flange portion is formed with a rail base receiving depression or seat 9 extending across transversely thereof adjacent each end and the bottom of each of the depressions or seats 9, 9 of the channel section B has a lug struck out

Application July 27, 1944, Serial No. 546,795

1 Claim. (Cl. 238—38)

1

This invention relates to new and useful improvements in railroad ties of the metallic type.

The main object of the present invention consists in providing a railroad tie assembly, consisting of two channel sections held back to back, with a depression of appropriate width for each rail and lugs projecting over the rail base in such a manner that after assembly of the channelled sections and rails, the latter, when filling the depression and held by means of the lugs in said depressions, will lock the tie assembly against any longitudinal displacement of the channelled sections relative to each other.

Other objects and advantages of the invention will become apparent to the reader of the following specification.

In the drawings:

Figure 1 represents a fragmentary top plan view showing one of the ties for two rails.

Figure 2 is a fragmentary sectional view taken substantially on the line 2—2 of Figure 1.

Figure 3 is a perspective view of one section of the tie.

Figure 4 is a perspective view of the section of the tie.

Figure 5 is a perspective view showing both sections of the tie in assembled relation.

Figure 6 is a fragmentary side elevational view showing one end of the tie section shown in Figure 3.

Figure 7 is a fragmentary sectional view taken substantially on the line 7—7 of Figure 2.

Figure 8 is a fragmentary plan view of a modified form.

Referring to the drawings wherein like numerals designate like parts, it can be seen in Figures 3, 4 and 5 that the tie 5 is made of a pair of channelled sections denoted by reference characters A and B. Each of these sections has its flange portions disposed horizontally, the central webs or walls of the channelled sections A and B being bolted together as disclosed in Figure 7. One of the sections, such as the section B, has its ends notched as at 6, while the corresponding ends of the other section A are provided with lugs 7 bent out at right angles from its web. The lugs 7 when the tie is assembled are disposed through the notches 6 of the section B, thus locking both sections firmly together.

Each of the channel sections A, B in its uppermost horizontal flange portion is formed with a rail base receiving depression or seat 9 extending across transversely thereof adjacent each end and the bottom of each of the depressions or seats 9, 9 of the channel section B has a lug struck out

2

disposed in definite direction and denoted by the numeral 10 while the depressions or seats 9 of the channel section A have portions struck out to provide lugs 11 disposed in the opposite direction, to the end that the lugs 10 of the section B will engage a rail foot at one side thereof while the staggered lugs 11 of the section A will engage the rail foot at the opposite side thereof. It will thus be noted that both channel sections may be cut out from one channel having all lugs 10, 11 pointing in the same direction.

A modified form of the invention is shown in Figure 8, and shows lugs 11a struck from the bottom of the depressions or seats between the longitudinal edge portions of the corresponding flange instead of at one longitudinal edge as in the first form of the invention described. Furthermore, this form of the invention which is denoted by reference character 5a has tongues 15 struck out from its vertical wall or web and bent at right angles for the purpose of anchorage in railroad ballast.

It will be noted that the bolted connections in conjunction with the retaining lugs and notches (features 6 and 7) prevent any possible longitudinal shifting of section A in relation to section B. This two-way assembling connection avoids relative displacement of parts, provides for strength and rigidity and takes shearing strain off of the bolts.

Obviously, a tie constructed in accordance with the above will be durable and will obviate the necessity of workmen driving spikes and replace the same when they become worn.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a metallic railroad tie assembly the combination of rails having a flat base, a pair of channelled rail supporting sections, mounted with their webs back to back, with their rail supporting flanges arranged in the same plane and in a substantially horizontal position, the said rail supporting flanges being provided with a pair of depressions running transversely across them, the depressions of adjacent channelled sections being aligned, and each depression being of the width of the rail base, rail base engaging lugs, cut out of the material of the seat, raised and projecting over the same for holding the rail on

its seat, the lugs on each channelled section being raised for engagement of the same side of the rail bases and the lugs on different sections being raised for engagement of different sides of the rail bases, the webs of the channelled sections being provided with connecting means for preventing the separation of the said sections in the longitudinal direction of the rail, said channel sections, after assembly on the rails, being locked in the transverse direction of the rail by the rail bases seated in the depressions and the rail base engaging lugs.

CHARLES C. JONES.
